No. 890,559.

PATENTED JUNE 9, 1908.

C. E. DODD.
CUFF HOLDER.
APPLICATION FILED NOV. 26, 1906

UNITED STATES PATENT OFFICE.

CHARLES E. DODD, OF WILLIAMSPORT, PENNSYLVANIA, ASSIGNOR TO M. S. DODD AND GEO. F. ERDMAN, OF WILLIAMSPORT, PENNSYLVANIA.

CUFF-HOLDER.

No. 890,559.

Specification of Letters Patent.

Patented June 9, 1908.

Application filed November 26, 1906. Serial No. 345,090.

To all whom it may concern:

Be it known that I, CHARLES E. DODD, a citizen of the United States, residing at Williamsport, in the county of Lycoming and State of Pennsylvania, have invented certain new and useful Improvements in Cuff-Holders, of which the following is a specification.

My invention relates to an improvement in cuff holders, and the object is to provide a simple and inexpensive article of manufacture, capable of being quickly applied to the cuff, and attached to the cuff button or the sleeve of the shirt.

With the foregoing objects in view, my invention consists in a cuff holder constructed and adapted for attachment to the sleeve button or sleeve, with equal facility, from either edge, and it further consists in certain novel features of construction and combinations of parts which will be herein-after described and pointed out in the claims.

In the accompanying drawings.—Figure 1 is a plan view of one form of my improved cuff holder. Fig. 2 is a view of the same from one edge. Fig. 3 is an end view looking toward the clasp. Fig. 4 is a fragmentary view showing a slightly modified means of connecting the shank and compound hook. Fig. 5 is a section through the same taken on the dotted lines shown in Fig. 4. Fig. 6 is a view showing a modified form of the compound hook. Fig. 7 is a view of the same taken at right angles to Fig. 6. Fig. 8 is a view showing a modified form of clasp, this being a single clasp instead of a double one as shown in Fig. 1. Fig. 9 is an edge view of the form shown in Fig. 8. Figs. 10 and 11 are views at right angles to each other, of a compound hook made of sheet metal. Figs. 12 and 13 are views at right angles to each other showing a slightly modified form of clasp composed of two superimposed coils of wire. Figs. 14 and 15 are two views at right angles to each other showing a modified form of compound hook similar to that shown in Figs. 1 and 2, with the addition of the guard 5. Fig. 16 is a view showing a swiveled spring clasp. Fig. 17 illustrates a slightly modified form of shank 1 in which the loops are angular instead of oval. Fig. 18 is a view showing the holder applied to a cuff.

This cuff holder may be made wholly or partly of wire; in the form shown in Figs. 1

and 2, it is composed of wire and the major portion of the device is constructed to lie wholly in one plane. The shank 1 is bent back and forth in zig-zag shape to form a plurality of open spring loops, the alternate loops being open at opposite sides and the wire being spring metal, the purpose of these loops is to receive the sleeve button from either edge, and the object of providing several of them is to adjust the cuff with respect to the sleeve to bring it down to the proper position for the wearer.

While, primarily, the purpose of this zig-zag shank is that described above, namely to permit the fastener to engage a sleeve button from either side, incidentally it is obvious that this form of shank will afford some resiliency, and yielding capacity, so that any sudden strain upon the cuff, when fastened, would neither tear it from the garment, nor tear the garment, and after yielding, it would resume its normal condition.

At one end, the wire is bent to form a compound hook 2, the purpose of which is to enter and maintain a position in the button holes of the cuff. The extreme end 3, of the compound hook is in the form of a tongue which has the combined function of facilitating the attachment of the fastener to the cuff and of preventing the holder from becoming accidentally detached therefrom. At the outer end of the compound hook, the wire forming it is preferably bent inwardly slightly as at 7 in the form of a concaved curve for the purpose of receiving and retaining in position the edge of the button hole which otherwise might have a tendency to slip from this part of the hook, but which slipping this incurve effectually prevents. At the opposite end of the shank, a clasp is formed and in the construction shown in Fig. 1, this is made by bending the wire around one or more times in the same plane, with the tongue 8, thus formed and the outer ends of the inside bend curved outwardly slightly to form a mouth 9 whereby the clasp is made to engage the edge of the sleeve opening from either side, thus forming a double clasp, and in this way, providing a device which will engage either edge of the sleeve opening with equal facility, so that each cuff holder is a right and left cuff holder so to speak, capable of being operated just as well with one hand as the other, and so that it will engage either edge of the sleeve opening.

While the foregoing is a general description of one form of my invention, it is perfectly obvious that other forms might be used, and for instance, the compound hook 5 might be made of sheet metal as shown in Figs. 10 and 11, one end of the metal forming this hook being secured to the shank by bending it around the end wires thereof in any approved manner. Likewise, it might 10 be found convenient to bind a piece of metal around the connection at the juncture between the zig-zag shank and the compound hook, as shown in Figs. 4 and 5.

It may be found desirable to employ a single clasp in lieu of a double clasp for engaging the edge of the fabric forming the sleeve. Such a clasp is shown in Figs. 8 and 9, and other forms are shown in Figs. 12 and 13. The form shown in these two last figures 20 consists merely of a spring ring composed of two turns of wire.

In still another form, of the cuff holder, I might find it desirable to use an ordinary spring clasp such as shown in Fig. 16. Likewise, the compound hook might be slightly 25 varied and instead of being composed of two leads of wire as shown in the construction heretofore described, it might be made of one lead of wire, as shown in Figs. 6 and 7, 30 with the extreme end bent upwardly to form a guard tongue and to facilitate the inserting of the hook into the button hole.

Still another form is shown in which the extreme end of the wire is bent outwardly at 35 the rear of the compound hook to form a guard 5 at the rear which extends parallel with the guard tongue 4, as shown in Figs. 14 and 15.

In Fig. 17, I have shown a slightly modified form of shank in which the loops are dia-

mond shaped, instead of oval, as this seems to be an obvious equivalent.

The foregoing are a few of many possible equivalent constructions which might be shown and described and it will be seen from 45 what I have disclosed, that a very simple and effective invention is provided for the performance of the functions desired.

Additional slight changes might be resorted to within the scope of the appended 50 claims in the form and arrangement of the several parts described without departing from the spirit and scope of my invention, and hence I do not wish to limit myself to the exact construction herein set forth, but:— 55

Having fully described my invention, what I claim as new and desire to secure by Letters Patent, is:—

1. As an article of manufacture, a cuff holder comprising a flat zig-zag shank having 60 spring loops opening alternately in opposite directions and having constricted openings to receive a button and fastening means located at each end of the zig-zag shank.

2. As an article of manufacture, a cuff 65 holder consisting of a shank portion comprising a continuous series of flat loops formed of a single piece of metal and having narrowed entrance openings, adjoining loops opening in opposite directions, and fastening 70 means located at each end of said shank portion.

In testimony whereof I have signed my name to this specification in the presence of two subscribing witnesses.

CHARLES E. DODD.
